UNITED STATES PATENT OFFICE.

KARL C. RANDALL, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

SUSPENSION-TYPE INSULATOR.

1,168,031.

Specification of Letters Patent. Patented Jan. 11, 1916.

Application filed May 4, 1915. Serial No. 25,726.

To all whom it may concern:

Be it known that I, KARL C. RANDALL, a citizen of the United States, and a resident of Edgewood Park, in the county of Allegheny and State of Pennsylvania, have invented a new and useful Improvement in Suspension-Type Insulators, of which the following is a specification.

My invention relates to insulators, and it has particular reference to suspension-type insulators adapted to insulate high-potential line conductors.

My insulating structure may be utilized for flexibly suspending high-potential conductors from supporting towers or poles, and moreover, it may be subjected to temporary mechanical deformations by reason of being swung by wind currents without decreasing the insulating properties of the structure.

In my insulating structure, I use a small amount only of insulating material and conducting material but the insulating and conducting members are so shaped and interrelated as to utilize the maximum insulating strength of the air.

When a difference of potential exists between adjacent conducting bodies, the air is subjected to stresses by reason of the electric field produced. A field of this character may be represented by means of lines called electrostatic flow-lines, the distribution and arrangement of which are dependent upon the shapes and sizes of the conducting bodies, their spacing, the character and shape of the insulating medium, and the potential to which the bodies are subjected.

In the present invention, I have utilized the principle disclosed in U. S. Patent No. 1,129,520. While the insulating bodies or members employed in my suspension-type insulator are of a standard form, the conducting bodies surrounding or inclosing the insulating members are so shaped that the stresses arising from the electrostatic flow-lines extending between the adjacent surfaces thereof are precluded from breaking down the interposed bodies of air, the insulating strength of which is to be utilized to its full value. It is known, as disclosed in the aforementioned patent, that the conducting bodies may be so formed that undue concentrations of electrostatic stresses upon the adjacent and opposed surfaces thereof may be substantially precluded.

An object of my invention is to provide an insulator of the aforementioned character in which the conducting bodies afford mechanical protection to the insulating bodies and shield them from surface accumulations of water and dust particles, and are so shaped as to preclude undue concentrations thereupon of electrostatic flow-lines. In this manner, a very compact and efficient insulator for high voltages is provided.

Referring to the drawing, the single figure of which is a view, partially in elevation and partially in section, of a structure embodying a form of my invention, a high-potential line conductor 1 engages a clamp 2 that is supported, by means of a link 3, from an insulating member 4 which constitutes the lowest insulating member of my suspension-type insulator 5. By means of an eyelet 6, the structure 5 and the associated line conductor 1 may be supported from any suitable tower or pole.

The suspension-type insulator 5 comprises a series of superposed bell-shaped conducting members 7 which are rigidly connected to the insulating members 4. The insulating members 4 are flexibly connected to one another by means of flexible connections 8, and a bell-shaped conducting member 7 is disposed on each insulating member 4 adjacent to the flexible connection 8. In the figure shown, the insulating members 4 constitute a standard type of strain insulator having a corrugated surface, as indicated. It is to be understood, however, that other forms of insulating members may be used.

The bell-shaped member 7, which is preferably spun from a sheet metal plate, is provided with an outer surface of double curvature. The upper portion 9 of the member 7 constitutes a curved surface having a relatively small radius of curvature and the lower portion 10 constitutes a curved surface having a relatively large radius of curvature. The bell-shaped members 7 are nested within, but spaced from, one another in such a manner that the upper portion 9 of a lower member is disposed adjacent to the lower portion 10 of an upper member. It will be understood that the radii of curvature of the portions 9 and 10 are comparatively large in order that the lines of force extending between adjacent conducting surfaces are precluded from forming undue concentrations and thereby subjecting the

interposed air spaces to stresses that will impair their insulating properties.

Inasmuch as strain insulators are subjected to temporary deformations by reason of winds, heavy air currents, etc., it is important that the adjacent conducting members 7 be so formed and connected as to permit of such deformations and, at the same time, be kept spaced from one another sufficient distances at all times to avoid decreasing the insulating strength of the support 5. The flexible connections 8 permit relative movements of the insulator sections under the above stated conditions, and the portions 9 and 10 of adjacent members 7 are of such shape and relative location as to maintain the desired insulating properties.

It will be noted that the metallic members 7 so inclose the insulators 4 as to protect them from mechanical shocks or blows and from the accumulation of dirt and other deposits which would decrease the insulating strength of the structure.

While I have shown and described one embodiment of my invention, it will be understood that many modifications may be made therein without departing from the spirit and scope of the appended claims.

I claim as my invention:

30 1. An insulating structure comprising a plurality of alternately-disposed conducting and insulating bodies, the insulating bodies being inclosed within the conducting bodies which consist of bell-shaped members having surfaces of double curvature of relatively large radii, the upper portions thereof having smaller radii of curvature than the lower portions.

40 2. An insulating structure comprising a plurality of alternately-disposed conducting and insulating bodies, the insulating bodies being inclosed within the conducting bodies and spaced therefrom, said conducting bodies being nested in, but spaced from, one another and consisting of bell-shaped members having surfaces of double curvature of relatively large radii, the upper portions thereof having smaller radii of curvature than the lower portions.

50 3. An insulating structure comprising a

plurality of alternately-disposed insulating and conducting bodies, the insulating bodies being flexibly connected to one another and the conducting bodies being rigidly supported upon the insulating bodies adjacent to said flexible connections, each of said conducting bodies surrounding the insulating body which is disposed immediately below and consisting of a bell-shaped member having a surface of double curvature of relatively large radii, said conducting bodies being so nested within one another as to preclude undue concentrations of electrostatic flow-lines thereupon.

4. A suspension-type insulator comprising a plurality of flexibly connected insulating members, conducting bodies disposed on the insulating members adjacent to said flexible connections, each of said conducting bodies surrounding the insulating member disposed immediately below, and consisting of a bell-shaped member having an exterior surface of double curvature, the upper portion thereof having a smaller radius of curvature than the lower portion, said conducting bodies being nested within one another so that the outer surfaces of the upper portions of the lower conducting bodies are adjacent to, but spaced from, the inner surfaces of the lower portions of the immediately superposed conducting bodies.

5. A suspension-type insulator comprising a plurality of flexibly connected insulating members, conducting bodies disposed on the insulating members adjacent to said flexible connections, each of said conducting bodies surrounding the insulating body disposed immediately below and consisting of a bell-shaped member having an exterior surface of double curvature, said conducting bodies being nested within, but spaced from, one another, the adjacently-disposed surfaces thereof being so formed as to preclude undue concentrations of electrostatic flow-lines thereupon.

In testimony whereof, I have hereunto subscribed my name this 29th day of April, 1915.

KARL C. RANDALL.
